QUICK ATTACHABLE AND DETACHABLE
HEAT CIRCULATOR

Noel S. Cole, Greenwood, Miss.

Application November 6, 1946, Serial No. 708,154

1 Claim. (Cl. 230—273)

This invention relates to a forced circulating heating attachment which is adapted to be used with gas heating burners for heating homes, as well as burners known as space burners or chill chasers.

An object of the invention is to provide an attachment which can be quickly attached or detached from a gas burner for providing a circulation of heat throughout the room.

Another object of the invention is to provide a device which is simple in construction, durable in use, efficient in operation, and can be inexpensively manufactured.

With the above and other objects in view, the invention consists of the novel details of construction, arrangement and combination of parts more fully hereinafter described, claimed and illustrated in the accompanying drawings in which:

Figure 1 is an elevational view of an embodiment of the invention as attached to a space gas burner or chill chaser;

Figure 2 is a side elevational view of Figure 1;

Figure 3 is a front elevational view of the device per se, and

Figure 4 is a sectional view on the line 4—4 of Figure 3.

Referring more in detail to the drawing, the reference numeral 10 designates the attachment embodying the invention which is adapted to be supported on the rear of a conventional gas or space burner 11, as will be later described.

The attachment comprises a substantial square shape box-like body having the front 12, sides 13, top 14 and bottom 15 all formed integral from a single sheet of metal.

Along the upper marginal edge of the front 12, there is secured thereto by bolts 16, the U-shaped supporting bracket 17 which extends for the full width of the attachment and by which the attachment is supported on the upper edge of the back of the heater 11, as shown in Figure 2, the shape of the bracket 17 conforming to the shape of the upper edge of the back of the heater.

Immediately below the lower edge of the bracket 17 the front is provided with a circular opening 18 which is centrally located transversely of the front, but not longitudinal thereof.

The sides, top and bottom each have inturned right angularly extending flanges 19 to which is secured by welding or the like, the back 20. The back 20 is provided with a centrally located circular opening 21 which is larger than the opening 18 in the front 12.

An electric motor 22 is secured to radially extending arms or brackets 23 at one end thereof, and the other ends of the arms are secured to the back 20 outwardly of the opening 21 on the rear of the back 20 by fasteners 24.

The drive shaft 25 of the motor extends inwardly of the opening 21, and has a fan 26 secured thereto in the conventional manner, as is common, the motor is provided with the electrical cord 27 having a plug 28 on the end thereof for connection to a source of electrical current.

In operation, the attachment is mounted as shown in Figures 1 and 2, and air drawn into the attachment through the opening 21 is forced outwardly of the opening 18 through the heater 11 to circulate hot air through the room in which the heater is installed.

It is believed that from the foregoing description, the operation and construction of the invention will be apparent to those skilled in the art, and it is to be understood that changes in the minor details of construction, arrangement and combination of parts may be resorted to, without departing from the spirit of the invention and the scope of the appended claim.

Having thus described the invention, what is claimed as new and desired to be secured by Letters Patent is:

An attachment for a gas burner, comprising a substantially square shaped box-like body, a U-shaped supporting bracket fixed to and extending the full length of said body at the upper front marginal edge thereof for supporting said body on said burner, a circular opening in the front of said body, a circular opening of greater circumference in the rear of said body, radially extending arms fixed to the rear of the body and extending over the said rear opening, an electric motor and fan operated thereby supported by said arms at the rear of said body, so that said fan is within said body and said motor is outwardly of said body.
